(57) **CLAIM**

The ornamental design for an electronic cigarette power supply device, as shown and described.

DESCRIPTION

1. Electronic cigarette power supply device

1.1 : Perspective

1.2 : Perspective

1.3 : Front

1.4 : Back

1.5 : Left

1.6 : Right

1.7 : Top

1.8 : Bottom

The present design relates to an electronic cigarette power supply device; reproduction 1.1 is a top perspective view of the electronic cigarette power supply device constituting the present design; reproduction 1.2 is a bottom perspective view thereof; reproduction 1.3 is a front view thereof; reproduction 1.4 is a rear view thereof; reproduction 1.5 is a left side view thereof; reproduction 1.6 is a right side view thereof; reproduction 1.7 is a top view thereof; and reproduction 1.8 is a bottom view thereof.

1 Claim, 8 Drawing Sheets
